UNITED STATES PATENT OFFICE

JOSEPH MOSS, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND

MECHANISM FOR HANDLING AND DISTRIBUTING FIBERS

Application filed March 12, 1929. Serial No. 346,479.

This invention is applicable to feed distributor systems on the order of those employed in cotton manufacture for the purpose of keeping the hoppers of the feed-mechanisms of cotton working machines supplied with material to be operated upon.

One form of these systems comprises a trough, or the like, extending the length of a series of hoppers, and having outlets 10 through which the fibrous material may discharge into the respective hoppers of the series, and an endless conveyor in connection with such trough provided with rakes, floats, or the like, which by the movement of the 15 endless conveyor are caused to travel along the trough, carrying with them fibrous material supplied at one point in the length of the trough, so that the fibrous material is discharged into the respective hoppers. Frequently, the source of supply for the fibrous 20 material is a condenser, in connection with a pneumatic conveyor system by means of which the fibrous material is transported from a remote source of supply to the point at 25 which it is supplied to the trough.

The invention comprises improvements in connection with delivery-chutes which are employed in connection with conveyors, hoppers, and outlets such as aforesaid; improved 30 means for supporting and guiding an endless conveyor and the so-called rakes or the equivalent thereof carried thereby; and improvements in the construction of the rakes.

The said improved means and improvements 35 are illustratively embodied in the feed distributor system shown in the accompanying drawings, in which,—

Fig. 1 is a side elevation of a distributing system embodying the features of the invention.

Fig. 2 is an elevation of the drive end of the machine, viewed from the right hand side in Fig. 1.

Fig. 3 is a view in vertical section on line 45 3, 3, of Fig. 1, on a larger scale than the preceding views.

Figs. 4 and 5 are, respectively, an end elevation of a rake-head, and a plan view of one end-portion thereof, both on a still larger 50 scale.

Fig. 6 is a side elevation of an end-portion of a rake-head having a tooth of modified character, secured in a different manner; Fig. 7 is a plan view thereof; and Fig. 8 is an end elevation thereof.

Fig. 9 is a view in vertical cross-section on line 9, 9, of Fig. 3, of a rake-head and one of the attached chain-links.

Fig. 10 is a sectional view illustrating one of the sprocket-wheels and its mounting.

Fig. 11 is a view in side elevation showing, more particularly, the construction of a telescopic chute.

Fig. 12 is a view in section transversely of the trough, on line 12, 12, of Fig. 11, looking 65 from the right hand side in Fig. 11.

Having reference to the drawings:

The trough of the illustrated feed distributor system comprises a bottom 1 and vertical sides 2, 2, extending the length of the 70 series of hoppers to which delivery is to be effected, which may be hopper feeders, for example, the said machines being arranged in a row, and the trough being supported on the tops of the sides 41, 41, of the hoppers 75 4, 4. Legs 3, 3, are provided in addition at the opposite ends of the trough. The trough bottom 1 at one end of the trough is turned up on a slant to form in conjunction with the terminal portions of sides 2, 2, a sort of hopper 80 for receiving the fibrous material that is to be distributed.

The fibrous material is caused to move lengthwise of the trough by the endless conveyor comprising a plurality of endless 85 sprocket-chains 6, arranged in parallelism and equipped with rakes 7, 7, the said chains being extended around sprocket-wheels 8, 81, fixed on transverse shafts 9, 91, located at the opposite ends of the system. For the actuation of the chains to cause the rakes to travel from end to end of the system, the shaft 9 is driven through suitable actuating devices, which may vary in practice as may be desired. In the present instance I have shown shaft 9 95 connected by means of bevel gears 10, 11, with a shaft 12 which is driven by means of a belt (not shown) applied to a pulley 13 upon the shaft 12.

Suitable outlets are formed in the trough.

bottom 1 through which fibrous material may discharge into the hoppers 4, 4. In accordance with the invention, the outlets have associated therewith chutes less in their cross-sectional dimensions than the hoppers and 5 extending downward into the hoppers below the tops of the walls of the hoppers. Preferably, I employ vertically-adjustable telescoping chutes respectively comprising a fixed section 14, Figs. 1, 11 and 12, depending from the bottom 1, and a vertically movable section 15 that is fitted upon the exterior of section 14 and is slidable thereon up and down to vary the height of the bottom dis- 10 charging end of the chute as it stands within the adjoining hopper 4. Suitable retaining means are provided to maintain the vertical adjustment that is given to the movable section 15 of a chute, such means herein comprising screw-threaded studs 16, 16, shown best in Fig. 11, that are fixed in the stationary section 14 of the chute and extend outwardly therefrom through vertical slots 17, Fig. 12, in the movable section 15, and thumb-nuts 18, 18, upon the projecting portions of the studs. The said nuts serve to fasten the movable section at the desired height through being screwed manually against the exterior surface of such section, so as to clamp the latter 25 tightly against the exterior of the fixed section 14.

A chute is provided in connection with each outlet in the bottom 1. The fibrous material received within the supply-receiving end of 30 the trough is dragged by means of the moving rakes to the opening at the top end of the first chute, the fibrous material discharging through such opening and through the chute into the hopper 4 below the same, until the 35 level of such material within such hopper reaches the bottom of the said chute. Thereafter, for the time being no more fibrous material enters the hopper, but fibrous material continues to enter the chute until the latter 40 is itself filled to the level of the bottom 1, after which the succeeding portions of fibrous material are carried along across the top of the filled chute to the next outlet, to pass in 45 similar manner down through the second chute into the second hopper. After the filling of this hopper up to the level of the bottom of the telescoping chute, and the subsequent filling of such chute, the fibrous material thereafter is carried on by the rakes 50 across the top of this second filled chute to the third chute, and so on throughout the series, any material that remains being dis- 55 charged by the rakes from the end of the trough at the drive-end of the machine, and thereby deposited in a suitable receptacle 60 placed under such end of the trough, or deposited upon the floor.

As the operation of a feeder lowers the level of the fiber in a hopper, the material 65 occupying the associated chute settles down,

whereupon additional flow of fiber into such chute takes place automatically. A conveyor-equipment having chutes which are of smaller cross-sectional dimensions than hoppers into which they extend is adapted to be 70 applied without reconstruction in connection with different hopper-assemblages, whatever the sizes of the hoppers. Again, it is not necessary that the spacing of the chutes in the series should correspond exactly 75 with the setting of the various hoppers with respect to one another. Furthermore, an important advantage of chutes having such relative cross-sectional dimensions, and in addition extending down within the hoppers 80 below the tops of the walls of the hoppers, is that after a hopper has become filled to the level of the delivery-mouth of the corresponding chute, so that further fiber ceases to pass down into the hopper, the fiber is permitted to spread transversely with relation to the mouth of the chute, as well as expand upward around the lower end of the chute. This freedom to spread transversely and expand vertically, involving more or less opening-out and exposure to the air, enables the accumulated fiber to assume by a natural action an improved condition for being worked in the machines to which it passes from the hoppers. The telescoping chutes herein described provide novel means for automatically controlling the height of the accumulation of fibrous material in the respective hoppers of the feeders, obviating with extreme simplicity the need for more complicated mechanical supply-governing devices. Through regulation of the said height, the rate at which the fiber is fed out from the hoppers by means of the usual spiked lifter-aprons, or equivalents, is controlled. The 90 higher the accumulation of fiber within a hopper the greater is the amount of fiber that is carried out of the hopper by the lifter-apron, and vice versa. The ability to adjust the hopper-mouths vertically within the 95 hoppers enables the proper rate of feed to be attained. It enables proper compensation for different kinds or grades of cotton. Different kinds or grades have different densities when they arrive at the hoppers. Some will 100 be compact and occupy smaller space than others. Consequently, the level of hopper-contents proper for one grade or kind might not answer for another.

Another feature of the invention comprises 105 improved means for mounting and supporting the sprockets 19, 19, which carry the upper or idle run of the endless chains bearing the rakes 7, 7. The said chains are of familiar link-belt type. Herein, as shown best in Fig. 10, each sprocket 19 is equipped with oppositely extended hubs 20, 20, which are provided with one or more wooden bushings 21; the sprocket having a central oil 110 reservoir 22, which in practice is filled with 115

oil through an oil-hole closed by a screw-plug 23. The sprockets 19, 19, are mounted upon shafts 24, 24, extending across the width of the trough and supported thereabove by brackets 25, 25. The said brackets are secured to the sides 2, 2, of the trough by bolts 26, 26, and also by tie-rods 27, 27, one of which is shown clearly in Fig. 3. Such tie-rods extend through sleeves 28 spacing the side-walls 2, 2, apart, and also through said side-walls and the brackets 25, 25, and receive nuts 271, 271, upon their extremities outside the brackets. The said shafts 24 are fixed in hubs 251, 251, at the upper ends of said brackets by clamping screws 29, 29, and the sprockets rotate freely upon the shafts, being held in properly spaced relations, according to the distance of chains 6, 6, apart from each other, by means of collars 30, 30, fixed by means of screws 301, 301, upon the shaft at the outer ends of the hubs of each sprocket.

This feature of the invention provides smooth-running supporting means for accurately guiding the upper or return run of the endless conveyor, with simple and inexpensive means for reducing friction and insuring the maintenance of adequate lubrication. The use of wood bushings obviates any overflowing of oil to get upon the fibrous material operated upon. Further, the method of combining the shafts 24, 24, with the sustaining brackets 25, 25, so that such shafts are in effect, tie-rods for the upper portions of the brackets, aids materially in strengthening the whole distributor organization and rendering it more rigid and freer from undesirable vibration.

Another feature of the invention has to do with the novel construction of the rakes which are mounted on the endless chains to engage the fiber received at one end of the trough and propel it lengthwise along the trough. These rakes respectively comprise heads of a length closely approximating the interior width of the trough between the opposite sides 2, 2, thereof, such heads being affixed to the plurality of endless chains at suitably spaced intervals to move with the said chains while maintaining transversely-extending relations at right angles to the chains. Each head is provided with a row of teeth or other fiber-engaging devices which extend down to or near the bottom of the trough, when on the lower or working run of the chains, in order that such row may operate to impel the fiber along the trough. In accordance with the invention, a rake comprises a head consisting of a bar 31 of U-shape in vertical cross-section, composed of rectangular channel iron, the side-flanges of which extend downward from the portion intermediate such flanges, the said intermediate portion constituting the back of the head, and the head having at each end a shoe 32. Preferably, though not necessarily

in all cases, such shoe is formed of hard wood that has been boiled in oil. The shoe occupies the channel of the head with its lower portion extending below the edges of the channel iron, and is secured by a bolt 33 put through the shoe and the flanges of the head. This shoe rests upon and is adapted to slide along a runway 34 formed of angle iron fixed on the interior of a side 2 of the trough. The pair of runways 34, 34, enable the rakes on the working run of the chains to travel the length of the trough with the ends of the rake-teeth in uniform close proximity to the bottom 1, but upheld out of contact therewith.

The drawings show two different constructions of rake teeth, and two different means of mounting them in connection with the rake-heads. In Figs. 6, 7, 8, the base portion of each tooth 35 is made rectangular in section, to fit closely between the depending flanges of the channel iron of the head, and is secured by a bolt 351 which passes transversely through said flanges and the interpolated base of the tooth. In Figs. 3, 4, and 5, however, the teeth 352, 352, are made of sheet metal, hollow, circular in cross-section, and tapering gradually from base to point. These teeth are each pressed into a tapering metal collar 36, within which the larger base end of the tooth wedges tightly. The base-ends of the teeth 352, 352, and the collars 36, 36, upon the same, occupy the interior of the channel iron constituting a rake-head, and are fastened to the intermediate portion constituting the back of the rake-head by means of rivets 37, 37, Fig. 5, put through said portion and through ears or lugs 38, 38, on the said collar. This metal tooth, provided with a tapering collar or socket, occupying the hollow of a channeled rake-head, with its butt or big end against the under side of the head, constitutes a very advantageous construction. There is no chance of such a tooth loosening or splitting and dropping out, to be carried into a preparing machine and do costly damage thereto.

The rake-heads are combined with the chains, which are preferably of the type known as "link-belt", by fastening said heads to flanges 39, Fig. 9, which are integrally formed on certain special links 390 which are inserted abreast of each other in the chains at appropriate intervals. Bolts 40 are put through the flanges 39 and through both flanges of the channel iron of the head and an interposed block 401 to fasten the rake-head and chain-link together. By this mounting, the rake-teeth are always held substantially at right angles to the chains so long as the latter are kept tight.

What I claim as my invention is:

1. In a mechanism for handling and distributing fiber to a series of hoppers, comprising a trough, and means for propelling fiber along said trough, the combination

therewith of chutes less in cross-sectional dimensions than the hoppers receiving the fiber as it is propelled along the trough, depending into the said hoppers, below the tops of the walls of the latter, and controlling the height of accumulation within the hoppers.

2. In a mechanism for handling and distributing fiber to a series of hoppers, comprising a trough, and means for propelling fiber along said trough, the said trough having outlets at the respective hoppers, the combination therewith of tubular chutes in connection with said outlets, less in cross-sectional dimensions than the hoppers, depending into the said hoppers, below the tops of the walls of the latter, and controlling the height of accumulation with the hoppers.

3. In a mechanism for handling and distributing fiber to a series of hoppers, comprising a trough, and means for propelling fiber along said trough, the combination therewith of adjustably telescoping tubular chutes less in cross-sectional dimensions than the hoppers, extending down within the hoppers below the tops of the walls of the latter, receiving the fiber from the trough and delivering it to the said hoppers, and adapted to keep them filled to the point where the fiber accumulated in the hoppers chokes the delivery through the chutes, the vertical adjustment serving to enable the height of delivered fiber accumulated in the respective hoppers to be varied to suit the qualities of the said fiber.

4. In a mechanism for handling and distributing fiber to a series of hoppers, comprising a trough, and means for propelling fiber along said trough, the combination therewith of automatic hopper-filling devices comprising tubular chutes less in cross-sectional dimensions than the hoppers, extending down within the hopper below the tops of the walls of the latter, receiving the fiber as it is propelled along the trough and respectively delivering fiber to the respective hoppers until further delivery to a given hopper is choked by the rising pile of delivered fiber below the chute, with the delivery ends of said chutes adapted for adjustment to vary the height of delivered fiber accumulated in said hoppers so as to enable such height to be proportioned in accord with the density of the fiber and the requirements in respect of expansion.

5. In a mechanism for handling fiber and distributing it to a series of hoppers, and comprising a trough having outlets in combination with said hoppers, and endless chains equipped with fiber-impelling devices traveling in said trough, the combination therewith of brackets rising from the sides of the trough, fixed non-rotating shafts constituting spacing tie-rods extending transversely with relation to said trough and chains and connecting said brackets in pairs at their upper ends, and wheels rotatably mounted upon

the said shafts and supporting the upper runs of said endless chains.

6. In a mechanism for handling fiber and distributing it to a series of hoppers, and comprising a trough having outlets in connection with said hoppers, and endless chains equipped with fiber-impelling devices traveling in said trough, the combination therewith of brackets secured to the sides of the trough, non-rotating shafts each having its ends secured in the upper ends of a pair of said brackets, and wheels rotatably mounted upon said shafts and supporting the upper runs of said chains.

7. In a mechanism for handling fiber and distributing it to a series of hoppers, and comprising a trough having outlets in connection with said hoppers, and endless chains traveling in said trough, the combination therewith of fiber-impelling devices comprising rakes having heads of U-shape in cross-section secured to said chains, fiber-engaging teeth secured to the heads within such U, and shoes occupying the ends of the respective heads and engaging with runways in connection with the sides of the trough.

8. In a mechanism for handling fiber and distributing it to a series of hoppers, and comprising a trough having outlets in connection with said hoppers, and endless chains traveling in said trough, the combination therewith of fiber-impelling devices comprising rakes having heads of U-shape in cross-section secured to said chains, and fiber-engaging teeth secured to the heads within such U.

9. In a mechanism for handling fiber and distributing it to a series of hoppers, and comprising a trough having outlets in connection with said hoppers, and endless chains traveling in said trough, the combination therewith of fiber-impelling devices comprising rakes having heads attached to said chains to travel therewith, collars affixed to said heads, and teeth tightly seated in said collars.

10. In a mechanism for handling fiber and distributing it to a series of hoppers, and comprising a trough having outlets in connection with said hoppers, and endless chains traveling in said trough, the combination therewith of fiber-impelling devices comprising heads secured to the said chains, tapering sheet-metal rake-teeth, and tapering collars in which the rake-teeth are tightly wedged, with said collars secured to said heads with the rake-teeth-ends abutting the under sides of such heads.

11. In a mechanism for handling fiber and distributing it to a series of hoppers, and comprising a trough having outlets in connection with said hoppers, and endless chains traveling in said trough, the combination therewith of fiber-impelling devices comprising heads secured to the said chains, ta-

pering sockets in connection with said heads, closed at their larger ends by the material of the heads, and tapering teeth seated in said sockets.

- 8 12. In a mechanism for handling fiber and distributing it to a series of hoppers, and comprising a trough having outlets in connection with said hoppers, and endless chains traveling in said trough, the combination therewith of fiber-impelling devices comprising heads secured to the said chains, tapering sockets in connection with said heads, closed at their larger ends by the material of the heads, tapering teeth seated in said 15 sockets, and a shoe at each end of the respective heads cooperating with runways in connection with the side-walls of the trough to guide the heads in their travel through the trough.
- 20 13. In a mechanism for handling fiber and distributing it to a series of hoppers, and comprising a trough having outlets in connection with said hoppers, and endless chains traveling in said trough, the combination 25 therewith of fiber-impelling devices comprising heads of channel iron secured to the said chains, tapering collars secured within the channels of said heads to the intermediate sections thereof, and tapering sheet-metal 30 teeth wedged in said collars.

14. In a mechanism for handling fiber and distributing it to a series of hoppers, and comprising a trough having outlets in connection with said hoppers, and endless chains traveling in said trough, the combination therewith of fiber-impelling rakes affixed by their heads to flanges on links of the chain, said flanges formed to stand at right angles to the plane of travel of the chains, so that the 40 rake-teeth stand out perpendicularly to the said plane of travel.
